UNITED STATES PATENT OFFICE.

AUGUST G. LIEBMAN, OF BUTTE, MONTANA, ASSIGNOR TO VIGNOLE'S RAIL CHAIR COMPANY, OF NEW YORK, N. Y., A CORPORATION OF DELAWARE.

SCREW-SPIKE FOR RAIL-CHAIRS.

1,126,531.

Specification of Letters Patent. Patented Jan. 26, 1915.

Application filed September 23, 1913. Serial No. 791,379.

To all whom it may concern:

Be it known that I, AUGUST G. LIEBMAN, citizen of the United States, residing at Butte, in the county of Silverbow and State 5 of Montana, have invented certain new and useful Improvements in Screw-Spikes for Rail-Chairs, of which the following is a specification.

This invention relates to railway track 10 appliance, and particularly to railway spikes.

The primary object of the invention is the provision of a spike peculiarly adapted for holding rail chairs or other rail supporting means solidly upon a tie, and in this connection to so construct the spike that it is adapted to engage rail adjusting means so that the spike not only forms the primary fastening for the tie but a secondary fastening for the rail.

20 A further object of the invention is to so form the spike that it may be readily screwed into the wood of a tie by various screw spike setting appliances now in use.

A further object of the invention is to so 25 form the spike that the rail may be adjusted and the secondary fastenings engaging the spike be adjusted without the necessity of removing the spike from the tie.

Other objects will appear in the course of 30 the following description.

The invention is illustrated in the accompanying drawings wherein:

Figure 1 is a perspective view of a screw spike constructed in accordance with the invention. Fig. 2 is a side elevation partly in section of the improved spike as applied to a rail chair. Fig. 3 is a view of a modified form of screw spike.

Corresponding and like parts are referred 40 to in the following description and indicated in all the views of the accompanying drawings by the same reference characters.

Referring particularly to Fig. 1, 2 designates generally a rail spike of the screw 45 type and comprising a straight shank having wood screw threads 3 extending from a point intermediate the ends of the spike to the lower extremity thereof. The upper portion of the spike is formed with screw threads 4 and intermediate the screw threads 4 and the screw threads 3 is formed an outwardly extending head or flange 5. The upper extremity of the spike is square or many sided in form to permit said spike 55 to be engaged by a wrench or other tool.

While it is to be understood that the improved screw spike may be used with any form of rail chair to which it is adapted, it is peculiarly adapted, for instance, to the form of rail chair shown in Fig. 2, this rail 60 chair forming the subject matter of an application for patent filed by me on the 10th day of July, 1913, Serial No. 778,402. In this figure, A designates a tie and B a rail. The tie A is supposed to be a wood tie and the rail B of any standard or conventional form. Disposed upon the tie A is a bed plate 6 having upwardly extending abutment 7, the inner face of each abutment being downwardly and inwardly inclined as 65 8. Disposed against the head of the rail at the base thereof is a downwardly and outwardly inclined rail brace 9.

Loosely mounted upon the screw spike 2 is a wedging member 10, the inner face of 75 which is inclined to correspond with the inclination of the outer face of the rail brace 9, while its outer face is slightly inclined downward and inward to coact with the inner face 8 of the abutment 7. This wedging member 10 is loose upon the spike and does not have screw threaded engagement therewith.

Engaging the screw threads 4 of the spike are nuts 11 and 12, the nut 12 being a lock 85 nut. It will now be seen that by turning down the nuts 11 and 12, the wedging member 10 will be forced into firm engagement between the abutment 7 and the rail brace 9 and will wedge the rail brace against the 90 rail B preventing any lateral movement of the rail or any vertical movement, it being understood that there are two of these wedging members disposed one at each end of the chair and a spike engaging with each 95 wedging member.

If it be desired to shift the rail B laterally, the nuts 11 and 12 of one spike are released, and the nuts on the other spike turned downwardly wedging the rail laterally until its correct position has been secured. By tightening up upon both sets of nuts, the rail is held in its shifted position. When it is desired to elevate the rail, shims are disposed between the rail base and the 100 bed plate 6, the nuts 11 and 12 being rotated in one direction to permit the insertion of this shim and then rotated in the opposite direction to clamp the rail firmly down upon the shim. It will be noted that this 105 110

adjustment of the rail may be secured without releasing the engagement of the spikes with the tie, and that thus it is only the secondary fastenings which are shifted, the 5 primary fastenings remaining precisely as they were.

In Fig. 3 there is shown a modified form of the spike in which the flange or head 5 is omitted. In this form of the device, 13 10 designates a bed plate or wear plate which rests upon the tie A and supports the rail B. This bed plate has at opposite points on each side of the rail B a perforation 14 surrounded by an upstanding wall 15, the 15 upper face of said wall being downwardly and outwardly beveled. The spike 2^a has a screw threaded portion 3^a designed to engage the wood of the tie, and a screw threaded portion 4^a, said spike terminating 20 at its upper end in a many sided head 16 adapted to be engaged by a wrench.

For the purpose of holding the rail to the tie, there is provided a clamping member 17 which is preferably annular in form and 25 beveled upon its under face to fit upon the bevel of the wall 15 and to engage over the inclined upper face of the rail base. This clamping member 17 has screw threaded engagement with the threads 4^a of the spike.

30 Fig. 3 shows that the invention may be applied to wear plates which simply act to support the rail and in which there is no lateral adjustment of the rail. It is obvious that shims may be inserted between the rail 35 base and the wear plate 13 by simply turning up the clamping member 17, inserting the shim and then turning down the clamping member until it bears solidly against the upper face of the rail base.

40 While two forms of rail supports to which

the improved spike is applicable have been illustrated, it will be understood that the spike may be used with any form of rail support or chair to which it is adapted.

What I claim is:

1. A screw spike of the character described comprising a straight shank, the lower portion of the spike being formed with wood screw threads, the spike intermediate its ends being formed with an enlarged head, the shank above said head being formed with screw threads adapted for engagement with nuts and the upper extremity of the spike being formed with a many sided head whereby a wrench may be 55 engaged with the spike.

2. A spike of the character described including a straight shank formed intermediate its ends with an integral laterally projecting head adapted to engage a support, 60 the lower portion of the spike below said head being formed with wood screw threads, and means engaging the upper portion of the spike adapted to operatively engage a rail.

3. A spike of the character described including a straight shank formed intermediate its end with integral laterally projecting head, the lower portion of the spike below said head being formed with wood 70 screw threads, and means engaging the upper portion of the spike adapted to operatively engage a rail, said means being adjustable.

In testimony whereof I affix my signature in presence of two witnesses.

AUGUST G. LIEBMANN. [L.S.]
